[57] CLAIM

The ornamental design for a game holder or similar article, substantially as shown and described.

DESCRIPTION

FIG. 1 is a perspective view of a game holder or similar article showing my new design;
FIG. 2 is a top plan view thereof;
FIG. 3 is a back elevational view thereof;
FIG. 4 is a bottom plan view thereof; and
FIG. 5 is a side elevational view thereof, the opposite side being a mirror image of the side shown.
